ADHESIVE APPLYING MEANS

John M. Brown, Lynwood, Calif.

Application April 21, 1947, Serial No. 742,794

7 Claims. (Cl. 91—47)

1

This invention relates to liquid adhesive applying means and in particular to means for applying adhesive to labels and the like.

One object of the invention is to provide an adhesive applying means of simple construction whereby a selected pattern of adhesive may be applied to a label. Another object is to provide an adhesive applicator in a labeling machine which will be immediately serviceable after an interruption of use. A further object is to provide an adhesive applicator which requires no cleanup after use. A still further object is to provide an adhesive applicator whose applying surface is stationary during use, and may be readily changed for another grid of any desired pattern. Another object is to provide an adhesive applicator which may be used without change for labels of varying sizes and shapes.

These and other objects are attained by my invention which will be understood from the following description and the accompanying drawings in which:

Fig. 1 is a side elevational view of a preferred form of my adhesive applicator;

Fig. 2 is a top plan view of the same;

Fig. 3 is an isometric fragmentary view showing the arrangement of grids and drainage spaces;

Fig. 4 is a fragmentary view in section showing an alternative form of the grid applicator.

Referring to the drawings, my adhesive applicator in its preferred form consists of a tank 11 having a somewhat elevated grid-containing portion 12 and a liquid level oscillating means 13 operatively connected to a portion of the tank adjacent thereto. The tank is provided with a cover 14 except in the portion occupied by the grid 15. The grid 15 consists of a series of spaced apart bars 16 placed on edge, with spacers 17 holding the grids apart, bolts 18 being provided to hold the bars and spacers rigidly together. Supporting legs 19 are also provided and these may be conveniently attached by the same long bolts 18. The legs 19 are adapted to hold the grid structure in a level position above the bottom of the tank with the top surfaces or edges of the grid bars being below the normal liquid level in the tank. The grid structure 15 is held in place by the frame 20 which is detachably mounted on the walls of the tank by the screws 21.

The liquid level oscillating means 13 in the form shown consists of a cylinder 22 having a piston head 23 on a piston rod 24, the piston rod extending upwardly through the cylinder head 25 and also extending on the other side of

2

the piston head 23 for a short distance to serve as a stop means 26 operating against the bottom of the tank 11 and limiting the downward stroke of the piston. A coil spring 27 is provided around the piston rod 24 abutting the piston head nut 28 at one end and the cylinder head 25 at the other, the spring urging the piston head to its lowest position. The piston rod 24 is provided at the end outside the cylinder with a connecting means 29 for an operating lever to operate the piston.

The liquid adhesive is put into the tank so that when the piston is in its down position, the level of the adhesive liquid is above the top surface A of the grid bars 16. The piston may be operated at any selected elevation in the cylinder, provided of course that sufficient liquid adhesive is supplied to fill the tank and the required portion of the cylinder. When the piston is raised, the level of the liquid is drawn below the top edges of the bars to the position B, by oscillating the piston up and down. The liquid level is thus oscillated to a position first above and then below the top edges of the bars 16.

25 A layer of liquid adhesive is left on the top surfaces of the bars when the main body of the liquid is withdrawn. During this portion of the cycle, the label is automatically placed on the grids and removed immediately carrying with it a pattern of adhesive bands corresponding to the pattern of the grid. The label is then transferred to the container to which it is to be applied. The layer of the adhesive on the top surfaces of the grids is then renewed by the raising of the liquid level over the grids by the downward movement of the piston head 23 in the cylinder 22.

The pattern of the grid structure may be arranged as desired to fit the particular labels 40 which are to be applied, or the bars may have varied thickness and spacing to effect transfer of greater or lesser amounts of adhesive. The grid pattern is, of course, made at least co-extensive with the labels and may be larger than the actual size of the label. For this reason, labels other than rectangular in shape may be handled. The top surfaces of the grids are constantly washed by the oscillating liquid adhesive so that it is unnecessary to have a grid structure exactly fitting the labels since only a single layer of glue remains on the grids after they have been submerged by the rising liquid level. The grid structure is easily changed when desired by merely removing the screws 21 hold-

ing the frame 20 in place, and replacing the grid by one of the desired grid patterns.

In using my new applicator, it may be desirable to use a label picker which holds the label in a level position over its entire surface. To attain this end, I prefer to use a label picker 30 consisting of a block 31 having a plurality of orifices 32 on its face, these orifices being connected by manifolds 33 to a connecting tube 34 which in turn is connected by a flexible hose 35 to a source of suction or reduced air pressure (not shown).

The label "L," during the operation of transferring to and from the applicator, is held against the block 31 by the suction applied through the orifice 32 distributed over the area of the label. The picker lever arm 40 mechanically moves the picker 30 in synchronism with the raising and lowering of the liquid level in the adhesive applicator tank, so that the label is placed on, and removed from the grid during the interval that the adhesive level is below the tops of the grid bar.

In the modification shown in Fig. 4, the grids 15A are arranged with a concave top surface so that a label picker 30A having a single suction cup 36 may be used for picking up the labels, the outside margin serving to press the label into the concave grid pattern 15A so that the adhesive is applied as an interrupted pattern over the entire surface of the label.

The advantages of my invention will be apparent. The applicator is simple in construction and there are no moving parts to the grid applicator itself. It is readily used with completely automatic labeling machines by suitable mechanical lever connections to operate the piston in the cylinder to oscillate the liquid, and to operate the picker lever 40. No cleanup of the adhesive container or the applicator grids is required when the operation of the machine is interrupted, either for overnight shutdowns or for shorter shutdowns during operating periods. It is only necessary to place a simple cover over the open portion above the grid in order to avoid evaporation of the adhesive solvent and to prevent the introduction of dust or other extraneous materials. The grid surfaces remain completely covered with liquid, and do not become caked with dried adhesive.

Other equivalent means for changing the liquid level in the tank may be used without departing from my invention, as defined in the appended claims.

I claim:

1. An applicator for liquid adhesives comprising a stationary container for the liquid adhesive having an uncovered portion co-extensive at least with the area over which the adhesive is to be applied; a grid in said uncovered portion having upper adhesive applying surfaces and intervening drainage channels lower than said applying surfaces into which the liquid adhesive may flow; and intermittent liquid level changing means operatively connected with the body of liquid adhesive in said container, whereby the level of the adhesive liquid is alternately raised above said upper adhesive applying surfaces and lowered below said surfaces.

2. An applicator for liquid adhesives comprising a stationary container for the liquid adhesive having an uncovered portion co-extensive at least with the area over which the adhesive is to be applied; a grid in said uncovered portion having upper adhesive applying surfaces and intervening drainage channels lower than said applying surfaces into which the liquid adhesive may flow; and piston and cylinder means operatively connected with the body of liquid adhesive in said container, whereby upon oscillation of said piston in said cylinder the level of the adhesive liquid is alternately raised above said applying surfaces and then lowered below said surfaces; and a label picker adapted to place individual labels against the grid of said applicator during the lowering cycle of said liquid level changing means, and to withdraw said label with adhesive thereon before the liquid level is raised above said grid.

3. In a machine for applying labels to containers; an applicator for applying liquid adhesive to individual labels comprising a stationary container for the liquid adhesive having an uncovered portion co-extensive at least with the area over which the adhesive is to be applied; a grid in said uncovered portion having upper adhesive applying surfaces and intervening drainage channels lower than said applying surfaces into which the liquid adhesive may flow; and piston and cylinder means operatively connected with the body of liquid adhesive in said container, whereby upon oscillation of said piston in said cylinder the level of the adhesive liquid is alternately raised above said applying surfaces and then lowered below said surfaces.

4. In a machine for applying labels to containers; an applicator for applying liquid adhesive to individual labels comprising a stationary container for the liquid adhesive having an uncovered portion co-extensive at least with the area over which the adhesive is to be applied; a grid in said uncovered portion having upper adhesive applying surfaces and intervening drainage channels lower than said applying surfaces into which the liquid adhesive may flow; and intermittent liquid level changing means operatively connected with the body of liquid adhesive in said container, whereby the level of the adhesive liquid is alternately raised above said applying surfaces and lowered below said surfaces; and a label picker adapted to place individual labels against said grid of said applicator during the lowering cycle of said liquid level changing means, and to withdraw said label with adhesive thereon before the liquid level is raised above said grid.

5. In a machine for applying labels to containers; an applicator for applying liquid adhesive to individual labels comprising a stationary container for the liquid adhesive having an uncovered portion co-extensive at least with the area over which the adhesive is to be applied; a grid in said uncovered portion having upper adhesive applying surfaces and intervening drainage channels lower than said applying surfaces into which the liquid adhesive may flow; an intermittent liquid level changing means operatively connected with the body of liquid adhesive in said container, whereby the level of the adhesive liquid is alternately raised above said applying surfaces and lowered below said surfaces; and a label picker adapted to place individual labels against said grid of said applicator during the lowering cycle of said liquid level changing means, and to withdraw said label with adhesive thereon before the liquid level is raised above said grid, said picker comprising a block co-extensive with the label to be picked up, a plurality of orifices on the face of said block, manifold means including a connection to a source of suction connecting said orifices, and lever connecting means for pressing the label against said grid and removing it with its adhering adhesive for application to a container.

6. In a machine for applying labels to containers; an applicator for applying liquid adhesive to individual labels comprising a stationary container for the liquid adhesive having an uncovered portion co-extensive at least with the area over which the adhesive is to be applied; a grid in said uncovered portion having upper adhesive applying surfaces and intervening drainage channels lower than said applying surfaces into which the liquid adhesive may flow; piston and cylinder means operatively connected with the body of liquid adhesive in said container, whereby upon oscillation of said piston in said cylinder the level of the adhesive liquid is alternately raised above said applying surfaces and then lowered below said surfaces; and a label picker adapted to place individual labels against the grid of said applicator during the lowering cycle of said liquid level changing means, and to withdraw said label with adhesive thereon before the liquid level is raised above said grid.

liquid level is raised above said grid, said picker comprising a block co-extensive with the label to be picked up, a plurality of orifices on the face of said block, manifold means including connection to a source of suction connecting said orifices, and lever connecting means for pressing the label against said grid and removing it with its adhering adhesive for application to a container.

6. In a machine for applying labels to containers, an applicator for applying liquid adhesive to individual labels comprising a stationary container for the liquid adhesive having an uncovered portion co-extensive at least with the area over which the adhesive is to be applied; a grid in said uncovered portion having upper adhesive applying surfaces and intervening drainage channels lower than said applying surfaces into which the liquid adhesive may flow; means for oscillating the liquid adhesive to alternately raise and lower its level above and below the top surfaces of said grid; and a label picker adapted to place individual labels against the grid of said applicator during the lower cycle of said liquid level changing means and to withdraw said label with adhesive thereon before the liquid level is raised above said grid, said picker comprising a flexible suction cup smaller than the label to be picked up attached to a connection body; a connecting body having a flexible tube adapted for connection to a source of suction holding said suction cup; and lever connecting means for pressing the cup and the attached label against said grid and removing said label with its adhering adhesive for application to a container.

7. In a machine for applying labels to containers, an applicator for applying liquid adhesive to individual labels comprising a stationary container for the liquid adhesive having an un-

- covered portion co-extensive at least with the area over which the adhesive is to be applied; a stationary grid in said uncovered portion having upper adhesive applying surfaces and intervening drainage channels lower than said applying surfaces into which the liquid adhesive may flow, said upper surfaces forming a concave area upon which a label is momentarily placed; means for oscillating the liquid adhesive to alternately raise and lower its level above and below the top surfaces of said grid; and a label picker adapted to place individual labels against the grid of said applicator during the lower cycle of said liquid level changing means and to withdraw said label with adhesive thereon before the liquid level is raised above said grid, said picker comprising a flexible suction cup smaller than the label to be picked up attached to a connection body; a connecting body having a flexible tube adapted for connection to a source of suction holding said suction cup; and lever connecting means for pressing the cup and the attached label against said grid and removing said label with its adhering adhesive for application to a container.
